CLAIM

The ornamental design for furniture, as shown and described.

DESCRIPTION

FIG. 1 is a front elevational view of furniture showing my new design.

FIG. 2 is an enlarged front view thereof.

FIG. 3 is a right-side elevational view thereof.

FIG. 4 is a top plan view thereof.

FIG. 5 is a bottom plan view thereof.

FIG. 6 is a left-side elevational view thereof; and,

FIG. 7 is a rear elevational view thereof.

The diagonal lines illustrated in FIGS. 6 and 7 are used to indicate that the claimed design is cut-away from the remaining unclaimed portion.

The broken lines in FIG. 1 depict environment and form no part of the claimed design.

1 Claim, 2 Drawing Sheets

FIG. 1

FIG. 2
